UNITED STATES PATENT OFFICE.

FRED C. RICHNER, OF ROCHESTER, NEW YORK.

EAVES-TROUGH HANGER.

Application filed June 17, 1926. Serial No. 116,754.

The present invention relates to eaves trough hangers and more particularly to a means for securing the outer edge of an eaves trough to the outer end of the supporting arm of the bracket, an object of the invention being to provide a simple and inexpensive securing means which may be readily connected to and disconnected from the eaves trough.

10 To these and other ends, the invention consists of certain parts and combinations of parts, all of which will be hereinafter described; the novel features being pointed out in the appended claim.

15 In the drawings:

Fig. 1 is a fragmentary front view of an eaves trough hanger;

Fig. 2 is a side view of the eaves trough hanger showing the eaves trough in section;

20 Fig. 3 is an end view of the securing device; and

Fig. 4 is a front view of the securing device before it is connected to the hanger and the eaves trough.

25 Referring more particularly to the illustrated embodiment of the invention, 1 indicates the eaves trough which has, as is customary, a rolled outer edge 2. The hanger embodies, in this instance, an attaching member comprising an anchoring portion 3 provided with openings 4 through which the anchoring portion may be secured to any suitable support. The attaching member also embodies a guide portion 5 which depends below the anchoring portion and is provided with a plurality of openings 6. On the guide is adjustable a supporting arm 7 which is held to the guide by a bolt 8 passed through the guide portion 5 and the 35 inner end of the arm. The outer end of the

arm is provided with a hook 9. The form of this supporting bracket is immaterial except that its outer end must be provided with a means such as the hook 9 through which the securing device may be connected 45 to the supporting arm.

The securing device, in this instance, comprises a bar 10 made of resilient material such as steel wire and having at its opposite ends two hooks 11 which are substantially of 50 U shape formation. In securing the eaves trough to the hanger, the inner edge of the trough is passed beneath an abutment 12 while the outer rolled edge 2 projects outwardly above the outer end of the supporting arm 7 and over the hook 9. The bar portion 10 of the securing device is now engaged with the hook near its central portion and then one hook 11 is passed over the rolled edge 2 of the eaves trough, after 55 which the other hook 11 is fitted over such rolled edge, thereby flexing the central portion 10 as shown in Fig. 1 of the drawings, and placing both hooks under tension, tending to pull and hold the eaves trough in 60 firm engagement with the supporting arm 7.

65 What I claim as my invention and desire to secure by Letters Patent is:

An eaves trough hanger comprising a supporting arm on which an eaves trough 70 rests, and a securing device for the outer edge of the trough embodying a pair of spaced hooks for engaging the outer edge of the eaves trough in spaced relation to opposite sides of the supporting arm, and a 75 resilient connecting portion between the hooks engaging the supporting arm at a point substantially midway between its ends in spaced relation to the hooks.

FRED C. RICHNER.
